CUSHION CLOSING DEVICE

Arthur J. Kay, Glendale, Calif.

Application January 28, 1939, Serial No. 253,300

5 Claims. (Cl. 254—67)

This invention relates to improvements in cushion closing devices.

The general object of the invention is to provide an improved apparatus for closing the filling 5 end of an overstuffed cushion.

Another object of the invention is to provide means for stretching the upper edge of the filling end of a cushion to assist in the closing of the end.

10 A further object of the invention is to provide novel metal clip means for closing the filling end of a cushion.

A still further object of the invention is to provide novel means for applying a metal clip 15 to a cushion for closing the filling end thereof.

Other objects and the advantages of my invention will be apparent from the following description taken in connection with the accompanying drawings, wherein:

20 Fig. 1 is a fragmentary front elevation of my improved cushion closing device;

Fig. 2 is a fragmentary section taken on line 2—2 of Fig. 1;

Fig. 3 is a fragmentary enlarged view of the 25 stretching mechanism partly in section;

Fig. 4 is a fragmentary section taken on line 4—4 of Fig. 1;

Fig. 5 is an enlarged side elevation of one of the metal clips;

30 Fig. 6 is an enlarged fragmentary side view of the clip closing apparatus showing it in an open position; and

Fig. 7 is a view similar to Fig. 6 showing the apparatus in a closed position.

35 Referring to the drawings by reference characters I have indicated my improved cushion closing device generally at 10. As shown the device 10 includes a table portion 12 supported by a suitable frame 13. Supported by the frame 40 13 adjacent the front of the device I provide a pair of spaced downwardly directed T irons 14 and 15 and spaced therebelow I provide a pair of upwardly directed T irons 16 and 17 which are supported by portions of the frame 13.

45 At one side of the frame 13 I provide an upwardly extending bracket member 18 having an inverted T iron 19 loosely pivotally connected thereto as at 20.

The T iron 19 when in a horizontal position 50 is spaced above the table 12 and extends thereacross to beyond the opposite side. Above the table 12 the iron 19 has a plate 21 secured thereto. The end of the iron 19 adjacent the pivot 20 extends outwardly beyond the bracket 55 18 a predetermined distance and has one end

of a downwardly inclined coiled spring 22 connected thereto as at 23 and the opposite end of the spring is anchored to a position of the frame 13 as at 24.

For retaining the iron 19 in a down position 5 I provide a latch member 25 located adjacent the opposite end of the iron 19 from the bracket 18. The latch 25 comprises a strip of metal 26 having a right angularly bent lip portion 27 at one end and at the opposite end is pivotally connected to the T iron 15 as at 28. When the latch 25 is in a vertical position as shown in Fig. 2, the loose pivotal connection 20 allows the T iron to be moved laterally below the lip 27. Thus it can be moved under the lip to retain the 10 iron 19 in a down position or it can be moved out from under the lip 27 to release the iron 19. When the iron 19 is released from the latch 25 the spring 22 swings the member 19 upward a desired distance.

20 On the plate 21 I provide a stretching mechanism which is indicated generally at 30. As shown the mechanism 30 includes a bracket 31 positioned intermediate the length of the plate 21 and a bracket 32 positioned adjacent the latch 25 end of the member 19.

The bracket 32 supports a bearing member 33 which includes a cylindrical shank 34 positioned in an aperture 35 in the bracket 32. (See Fig. 4.) The shank 34 terminates in a reduced 30 threaded portion 36 on which a washer 37 and nut 38 are positioned. The bearing member 33 extends beyond the front edge of the plate 21 and has an aperture 39 therein the axis of which is parallel to the edge of the plate 21.

35 The bracket 31 includes an integral bearing portion 40 which extends outwardly beyond the front edge of the plate 21 and has an open topped slot 41 therein in line with the aperture 39 in the bearing 33.

40 Positioned in the aperture 39 of the bearing 33 I provide a hollow rod 42 which includes a crank portion 43 on the end thereof adjacent the bracket 32. The rod 42 when in a horizontal position extends beyond the bearing 40 of the 45 bracket 31 and is positioned in the slot 41. From a location adjacent the bracket 32 to the opposite end the rod is externally threaded with a right hand thread as indicated at 44. At the side of the bearing 33 opposite the bracket 31 the 50 rod 42 has a collar 45 thereon which is secured to the rod by a pin 46. At the side of the bearing 40 opposite the bracket 32 the rod has a tip member 47 thereon.

55 The tip 47 has a recess 48 opening through one

end thereof in which the end of the rod 42 is positioned and secured thereto by pins 49. The tip 47 further includes a reduced aperture 50 which is threaded with a left hand thread and which opens into the recess 48.

Positioned on the rod 42 between the bearings 33 and 40 I provide a grip member 51. As shown the grip member is formed of a flat strip of metal and includes a body portion 52 and an angularly bent leg portion 53. The body portion 52 has an aperture 54 therein in which the rod 42 is positioned. The aperture 54 is of greater diameter than the rod 44 and is drilled at an angle to the faces of the body 52 so that when the body is tilted in one direction as shown in Fig. 3 opposite edges of the aperture will engage the threads 44 at the top and bottom of the rod. Thus when the rod 42 is rotated by the crank 43 the threads will move the grip member along the threaded portion of the rod. When the grip body 52 is moved to a vertical position the edges of the aperture 54 do not engage the threads 44 and the grip member may be freely moved along the rod 42.

The leg portion 53 of the grip 51 has a recess 55 therein which opens through the lower end of the leg and a threaded aperture 56 which intersects the recess 55. Positioned in the recess 55 I provide a small rod 57 which projects beyond the lower end of the leg 53 and terminates in a pointed end 58.

The rod 57 is retained in position by a clamp screw 59 positioned in the threaded aperture 56. Positioned in the hollow rod 42 I provide a reduced rod 60 which includes a left hand threaded portion 61 which engages the threads of the tip aperture 50. The rod 60 further includes a downwardly directed angularly bent end portion 62 which has a recess 63 opening through the lower end thereof and a threaded aperture 64 intersecting the recess 63. Positioned in the recess 63 I provide a small rod 65 which extends beyond the lower end of the rod 60 and terminates in a pointed end 66. The rod 65 is retained by a clamp screw 67 which is positioned in the threaded aperture 64.

When the grip 51 is in a position to engage the threads 44 of the rod 42 and the rod 42 is rotated as previously described, the tip 47 rotates with it and the engagement of the threads 50 thereof with the threads 61 of the rod 60 cause the rod 60, when it is held from turning, to move in a direction opposite to the direction of the grip member 51 is moved.

On the front of the frame 13 I provide a carriage member 70 which includes a vertical body portion 71 and an outwardly extending horizontal table portion 72. Adjacent the upper end the body 71 includes a pair of spaced inwardly extending brackets 73 and spaced therebelow a pair of spaced inwardly extending brackets 74. Each of the brackets 73 rotatably supports a pair of flanged wheels 75 one of which engages the lower edge of the web of the T iron 14 and the other engages the lower edge of the web of the T iron 15.

Each of the brackets 74 rotatably supports a pair of flanged wheels 76 one of which engages the upper end of the web of the inverted T iron 16 and the other the upper edge of the web of the inverted T iron 17.

At the front the frame 13 includes a channel iron 77 below the inverted T iron 16 and a channel iron 78 adjacent the bottom of the frame. Adjacent the channel 77 the body 71 on each side

includes a bracket portion 79 which rotatably supports a roller 80 which engages the front flange of the channel 77.

Adjacent the channel 78 the body 71 on each side includes a bracket portion 81 which rotatably supports a roller 82 which engages the front flange of the channel 78.

Intermediate the width thereof and adjacent the lower end the body 71 includes a pair of spaced outwardly extending lugs 83 to which one end of a foot lever 84 is pivotally secured as at 85.

The lever 84 at the end opposite the pivot 85 includes an enlarged foot plate 86 and is resiliently urged upwardly a desired distance by a coiled spring 87 one end of which is connected to the lever as at 88 and the opposite end is anchored to a portion of the carriage 70 as at 89.

The table 72 has an open topped dovetail groove 90 therein and supports a slide member 91. The slide member 91 includes a base 92 having a depending dovetail boss 93 thereon positioned in the dovetail groove 90. The base 92 has a pair of spaced bracket portions 94 extending upwardly therefrom which support a closing member 95.

The closing member 95 is made in the form of a pair of jaws having two sections 96 and 97 pivotally mounted on a pin 98 supported in the brackets 94.

On the side of the brackets 94 nearest to the table 12 the section 96 includes an elongated head portion 99 having a semi-cylindrical recess 100 in the under face thereof and on the opposite side includes a lever and hand grip portion 101.

On the same radius from the pivot 98 as the head 99 the section 97 includes an elongated head portion 102 having a semi-cylindrical recess 103 in the upper face thereof and on the opposite side of the pivot includes a lever portion 104.

Below the lever 101 I provide a cam member 105 which is suitably secured to a shaft 106 rotatably supported by the brackets 94. At one side of the brackets the shaft 106 has a lever member 107 thereon which includes a handle portion 108. The cam member 105 includes an arcuate cam surface 109 which when the member 105 is swung in one direction swings the lever 101 upwardly and the head 99 thereof downwardly and when the member 105 is swung in the opposite direction allows the lever 101 to swing downwardly and the head 99 thereof upwardly.

One end of a pair of link bars 110 is pivotally connected to the lever 104 as at 112 and the opposite end of the bars is pivotally connected as at 113 to the foot lever 84 intermediate the length thereof. Thus when the foot lever 84 is depressed as shown in Fig. 2, the link bars 110 will swing the lever 104 downwardly and the head 102 thereof upwardly.

The device 10 is particularly adapted for use in closing one end of overstuffed seat cushions such as the cushion 114. This type of cushion usually has corded edges as indicated at 115. When making this type of cushion all the sides are sewed shut except the upper edge of the material at one end as indicated at 116. Suitable stuffing material such as indicated at 117 is then placed within the cushion and then the edge 116 is sewed shut.

With the device 10 after the cushion is stuffed and ready to be closed it is laid on the table 12 below the plate 21 with the open end projecting beyond the edge of the table. The member 19 is swung downwardly and the plate 21 engages the upper face of the cushion and compresses it as shown in Fig. 2. The member 19 and the plate 75

21 are retained in this down position by the latch 25 as previously described.

The operator then inserts the pointed rod 65 of the stretching mechanism 30 through the cushion adjacent one corded upper edge as clearly shown in Fig. 1 and then moves the grip member 51 to a convenient location and inserts the pointed rod 57 through the opposite corded edge. In so doing the body 52 of the grip is inclined and engages the threads 44 of the rod 42 as previously described. Thereafter the operator rotates the rod 42 by means of the crank 43 to cause the grip 51 and the rod 60 to move away from each other as previously described thereby stretching the upper edge of the cushion. Thereafter the loose material 116 may be sewed to the upper corded edge if desired, but I prefer to secure the material 116 to the corded edge by a plurality of metal clamps 120 such as shown in Fig. 5.

20 The clamps 120 are formed of a single piece of metal arcuately bent with the edges thereof spaced apart and saw tooth notched to form a plurality of sharp teeth 121. The space between the edges of the clamp is sufficient that the clamp 25 can be positioned over the upper corded edge of the cushion as shown in Fig. 6. When the clamp is positioned on the corded edge the upper end of the loose material 116 is positioned in the clamp between the inner surface thereof and the 30 lower portion of the corded edge. The clamp 120 is held in place by hand and then the operator grasps the hand grip lever 101 with the other hand and moves the carriage 70 to a position wherein the heads 99 and 102 are in line with the clamp.

35 The operator then moves the slide member 91 towards the cushion until the heads 99 and 102 are in the correct position above and below the clamp as shown in Fig. 6. The operator then swings the cam member 105 upwardly as previously described thereby moving the head 99 downwardly into engagement with the clamp 120 which becomes positioned in the recess 100. Thereafter the operator places a foot on the foot place 86 and pushes it downwardly thereby swinging the foot lever 84 downwardly which through the medium of the link bars 110 swings the lever 104 downwardly and the head 102 upwardly into engagement with the clamp 120 which becomes positioned in the recess 103. Continued movement of the head 102 towards the head 99 squeezes the clamp closed tightly around the corded edge thereby firmly securing the loose material 116 to the corded edge.

50 Thereafter the operator releases the pressure on the foot lever and swings the cam member 105 downwardly whereupon the closing mechanism 95 swings to an open position. This operation of the closing mechanism 95 is repeated until a sufficient number of the clamps 120 have been placed in position to entirely close the previous open end of the cushion.

55 The operator then actuates the stretching mechanism 30 to move the grip 51 and the rod 60 towards each other to relieve the tension whereupon the grip member can be freely moved to free the pointed rod 57 from the cushion and then the pointed rod 65 is removed from the cushion. Thereafter the operator releases the member 19 from the latch 25 as previously described and the spring 22 swings the member 19 and the clamp plate upwardly a predetermined distance whereupon the cushion 114 is free to be removed from the table 12.

75 From the foregoing description it will be ap-

parent that I have provided a novel cushion closing device which is simple in construction and highly efficient in use.

Having thus described my invention I claim:

1. In a cushion closing apparatus a stretching mechanism including spaced supports, a rod rotatably mounted on said supports, said rod including a threaded portion, a grip member having an aperture receiving the threaded portion of the rod, said grip member having a pointed end, a tip on said rod, said tip having a threaded aperture therein, the threads of said tip aperture being reversed with respect to the rod threads, said tip having a pointed end. 5

10 15 20 2. For use in closing a cushion, a stretching mechanism including a rod, said rod including a threaded portion, a grip member having an aperture receiving the threaded portion of the rod, said grip member having a pointed end, a tip on said rod, said tip having a threaded aperture therein, the threads of said tip aperture being reversed with respect to the rod threads, said tip having a pointed end.

25 3. In a cushion closing apparatus, a stretching mechanism including spaced supports, a rod rotatably mounted on said supports, a grip member on said rod, said grip member including a pointed end, a tip member on said rod, said tip member including a pointed end, and means to cause said tip member to move back and forth 30 relative to the grip member.

35 4. In a cushion closing apparatus, a stretching mechanism including spaced supports, a rod rotatably mounted on said supports, said rod including a threaded portion, a grip member shiftably mounted on said threaded portion, said grip member including an end portion having a pointed member thereon, a tip member secured to said rod, said rod including an internally threaded end portion and said tip member including internal threads aligned with said internal threads of said rod member, a reduced rod threadedly engaging the threads of the tip member and the internal threads of said rod, the internal threads of said rod being reversed with respect to the external threads of said rod, said reduced rod including an end portion having a pointed member thereon. 40 45

50 5. In a cushion closing apparatus, a stretching mechanism including spaced supports, a rod rotatably mounted on said supports, said rod including a threaded portion, a grip member including a body having an aperture therein receiving said rod, said aperture being of greater diameter than the diameter of the rod and the walls defining the aperture being inclined at an angle to the face of the grip member so that opposite edges of the aperture wall engage the threaded portions of the rod, said grip member including a portion arranged at an angle of the body, said portion having a pointed member removably mounted thereon, a tip member threaded on said rod, said rod including an internally threaded end portion and said tip member including an internally threaded portion aligned with the internal threads of said rod member, a reduced rod threadedly engaging the threads of the tip member and the internal threads of said rod, the internal threads of said rod being reversed with respect to the external threads of said rod, said reduced rod including a bent end portion and a pointed member removably mounted on the bent end portion. 55 60
